[57] **CLAIM**

The ornamental design for set of front and back cover panels for a directory, as shown and described.

DESCRIPTION

FIG. 1 is a front view of a set of front and back cover panels for a directory showing our new design, the undisclosed rear being flat and plain;

FIG. 2 is an enlarged front view of the front cover panel as seen in FIG. 1, the undisclosed rear being flat and plain; and, FIG. 3 is an enlarged front view of the back cover panel as seen in FIG. 1, the undisclosed rear being flat and plain.

It is understood that the set of front and back cover panels for a directory are of conventional thickness.
